TRAILERABLE BOAT HULL

Leonard Elliot Field, 21 Woking St., Oxford Park,
Brisbane, Queensland, Australia

Continuation-in-part of design application Ser. No. 13,178,
Aug. 19, 1968. This application Aug. 11, 1969, Ser.
No. 18,633

Term of patent 14 years

Int. Cl. D12—06

U.S. Cl. D71—1

FIG. 1.

FIG. 2.

FIG. 3.

FIG. 4.

FIG. 6.

FIG. 5.

FIG. 7.

FIG. 8.

FIG. 1 is a side elevational view of a trailerable boat hull showing my new design, the opposite side being a mirror image thereof.

FIG. 2 is a bottom plan view thereof.

FIG. 3 is a front elevational view showing outriggers hinged back onto cabin deck.

FIG. 4 is a front elevational view of FIG. 1.

FIG. 5 is a rear elevational view thereof.

FIG. 6 is a rear elevational view showing outriggers hinged back onto cabin back.

FIG. 7 is a side elevational view showing outriggers hinged on top of cabin deck, the opposite side being a mirror image thereof.

FIG. 8 is a bottom plan view showing outriggers hinged onto cabin deck.

This is a continuation-in-part of design application Ser. No. D. 13,178, filed Aug. 19, 1968.

I claim:

The ornamental design for a trailerable boat hull, as shown and described.
